UNITED STATES PATENT OFFICE.

RICHARD A. LEADBETTER, OF DETROIT, MICHIGAN, ASSIGNOR TO THE FARRAND COMPANY, OF DETROIT, MICHIGAN, A CORPORATION OF MICHIGAN.

TRANSPOSING-TRACKER FOR MECHANICAL MUSIC-PLAYERS.

1,145,426.

Specification of Letters Patent.

Patented July 6, 1915.

Application filed July 31, 1911. Serial No. 641,477.

To all whom it may concern:

Be it known that I, RICHARD A. LEADBETTER, a citizen of the United States of America, residing at Detroit, in the county of Wayne and State of Michigan, have invented certain new and useful Improvements in Transposing-Trackers for Mechanical Music-Players, of which the following is a specification, reference being had thereto in to the accompanying drawings.

The invention relates to mechanical music players of that type in which the perforated music sheet is drawn over a tracker and controls the operation of the mechanism.

15 It is the object of the present invention to provide a simple and effective means for adjusting the music sheet and its carrying rolls laterally with respect to the tracker whereby a transposition in key may be effected.

20 To this end, the invention consists in a construction as hereinafter set forth.

In the drawings, Figure 1 is a front elevation of the construction; Fig. 2 is an end elevation thereof.

25 A is the tracker, which is provided with a series of ports B controlled by the music sheet, and which is mounted between stationary plates or standards C of the tracker box.

30 D is the music winding roll, and E F are the alined spindles for the music-holding roll and by which the music is rewound.

To provide for the transposition of the music, the winding roll D and spindles E F are mounted in a frame which is adjustable and is independent from the tracker box. This adjustable frame preferably comprises frame members G H arranged at opposite ends of the tracker box and which are secured to each other by connecting rods I J passing above and below said box. The frame members G H may be made of cast metal, and each is preferably provided with a pair of spacing bars K L in which separated bearings for the various spindles are formed. As illustrated, the frame member G has the bearings M M' for the spindle E, and bearings O O' for the spindle P of the winding roll D.

35 Q is the counter shaft on which the shiftable clutch R is sleeved, by which motion is alternatively communicated to the winding spindle P and to the sprocket S connected to the re-winding spindle E. To permit of the adjustment of the spindle-carrying

frame, the rods I J are slidably secured in bearings arranged at the top and bottom of the tracker end plates C.

U is a shifting rod for the adjustable frame operated by any suitable control connection (not shown), and V is a rod for controlling the shiftable clutch R. To permit of shifting the spindle-carrying frame without changing the adjustment of the clutch R, the latter is preferably operated through the medium of bell-crank levers W W' and a connecting link X. The bell-crank lever W' is directly connected with the rod V, and is fulcrumed on a stationary bracket Y. The bell-crank W is fulcrumed upon a bracket Z on the frame member G, and is therefore shiftable with said frame, but as the rod X is arranged at right angles to the line of adjustment of said frame this movement will not change the position of the bell-crank levers or the clutch R.

In operation, the music sheet is carried by the winding and music holding rolls, and is therefore shiftable with the frame members G H and spindles journaled thereon. On the other hand, the tracker A is stationary, so that with each adjustment of the music sheet a different registration is obtained in relation to the ports B. The range of adjustment is sufficient to obtain all of the various changes in the key desired.

What I claim as my invention is,

1. The combination with a stationary tracker and a tracker box therefor, of an adjustable frame comprising opposite end portions outside of said tracker box, music-holding spindles journaled in said end portions of the frame projecting through apertures in said tracker box into the latter, mechanism for adjusting said frame relative to the tracker box, mechanism adapted to alternatively wind and rewind the music, and means for controlling said mechanism comprising an adjustable clutch carried by said frame, and an operating connection for said clutch, and a stationary bracket to which a portion of said operating mechanism is connected.

2. The combination with a stationary tracker and a tracker box therefor, of a frame adjustable longitudinally of the tracker, music holding spindles journaled in said frame and extending into the tracker box at each end thereof, mechanism for adjusting the frame relative to the tracker,

mechanism adapted to alternatively wind and re-wind the music, and means for controlling said mechanism, comprising an adjustable clutch carried by said frame, an operating connection for said clutch and a stationary bracket to which a portion of said operating mechanism is connected.

3. The combination with a stationary tracker and a tracker box therefor, of an adjustable frame comprising opposite end portions outside of said tracker box, music holding spindles journaled in said end portions of the frame, projecting through apertures in said tracker box into the latter, mechanism for adjusting said frame relative to the tracker box, mechanism carried by one of the end portions of the frame adapted to alternatively wind and re-wind the music, and means for controlling said mechanism, comprising an adjustable clutch carried by said frame, an operating connection for said clutch and a stationary bracket to which a portion of said operating mechanism is connected.

4. The combination with a stationary tracker and a tracker box therefor, of an adjustable frame, comprising opposite end portions outside of said tracker box, music holding spindles journaled in said end portions of the frame, projecting through apertures in said tracker box into the latter, mechanism for adjusting said frame relative to the tracker box, mechanism adapted to alternatively wind and re-wind the music, and means for controlling said mechanism, comprising an adjustable clutch carried by one of the end portions of the frame, a bell crank actuating said clutch and carried by the frame, a stationary bracket, a bell crank mounted thereon, a rod actuating the first bell crank from the second disposed substantially at right angles with the direction of the adjustment of the frame, and means for rocking the second bell crank.

5. The combination with a frame and a tracker relatively adjustable longitudinally of the same, of music holding spindles journaled in said frame respectively adjacent to the tracker extremities, mechanism for actuating relative adjustment between the frame and tracker, mechanism adapted to alterna-

tively wind and re-wind the music, and means for controlling said mechanism comprising an adjustable clutch carried by said frame, an operating connection for said clutch, and a stationary bracket to which a portion of said operating mechanism is connected.

6. The combination with a tracker box of a relatively adjustable tracker and frame, the former within said box and the latter comprising opposite end portions outside of said tracker box, music holding spindles journaled in said end portions of the frame projecting through apertures in said tracker box into the same, mechanism for accomplishing relative adjustment of the frame and tracker, mechanism adapted to alternatively wind and re-wind the music, and means for controlling said mechanism carried by the frame in one of its end portions, comprising an adjustable clutch, an operating connection for said clutch and a stationary bracket to which a portion of said operating mechanism is connected.

7. The combination with a stationary tracker and a tracker box therefor including plates at the opposite ends of the tracker, of an adjustable frame comprising opposite end portions outside of said tracker box and including a pair of slide rods parallel to the tracker, bearings carried by the end plates of the tracker box receiving said slide rods, music holding spindles journaled in said end portions of the frame, projecting through apertures in said tracker box into the same, mechanism for adjusting said frame relative to the tracker box, mechanism adapted to alternatively wind and re-wind the music, and means for controlling said mechanism comprising an adjustable clutch carried by said frame, an operating connection for said clutch and a stationary bracket to which a portion of said operating mechanism is connected.

In testimony whereof I affix my signature in presence of two witnesses.

RICHARD A. LEADBETER.
